CLAIM

The ornamental design of a device for preventing inhalation of airborne material, as shown and described.

DESCRIPTION

FIG. 1 is a perspective view of a device for preventing inhalation of airborne material, configured in accordance with the present invention;

FIG. 2 is a front view of the device shown in FIG. 1;

FIG. 3 is a back of the device shown in FIG. 1;

FIG. 4 is a right side view of the device shown in FIG. 1;

FIG. 5 is a left side view of the device shown in FIG. 1;

FIG. 6 is a top view of the device shown in FIG. 1;

FIG. 7 is a bottom view of the device shown in FIG. 1; and,

FIG. 8 is a perspective view of the device shown in FIG. 1 on a user.

The broken lines in the drawing are included for the purpose of illustration and form no part of the claimed design. In embodiments other than those illustrated, lines that are currently illustrated as solid lines may be redrawn as broken lines, and/or lines that are currently illustrated with broken lines can be redrawn with solid lines. Color and texture may or may not form part of the claimed design without departing from the design disclosed. The addition of further physical elements such as ribs, ridges, textures, support members, and/or dimples are not excluded. The scope of the present disclosure encompasses all lines illustrated, whether broken or solid.
